Attala.

UNITED STATES PATENT OFFICE.

CASS L. KENNICOTT, OF CHICAGO HEIGHTS, ILLINOIS, ASSIGNOR OF ONE-HALF TO THE PERMUTIT COMPANY, OF NEW YORK, N. Y., A CORPORATION OF DELAWARE.

MEANS FOR REGULATING THE FEED OF CHEMICALS IN WATER-SOFTENING APPARATUS.

1,272,054.

Specification of Letters Patent.

Patented July 9, 1918.

Application filed March 20, 1916. Serial No. 85,386.

To all whom it may concern:

- Be it known that I, CASS L. KENNICOTT, a citizen of the United States, residing at Chicago Heights, in the county of Cook and State of Illinois, have invented a new and useful Improvement in Means for Regulating the Feed of Chemicals in Water-Softening Apparatus, of which the following is a specification.
- 10 My invention relates to certain new and useful improvements in water-softening apparatus, and more particularly to a means for regulating the feed of chemicals in an apparatus of this kind.
- 15 My invention will be more fully understood from the following detailed description of a specific embodiment thereof, taken in connection with the accompanying drawings in which Figure 1 is a diagrammatical 20 vertical sectional view of the essential portions of a water-softening apparatus constructed in accordance with my invention, and Fig. 2 is an enlarged sectional view to the regulating valve for the displacing 25 water.

Referring more particularly to the drawings, the numeral 1 designates a vertical cylindrical sedimentation tank, which may be provided with the usual conical bottom 2, 30 and drain or sludge draw-off 3. In this sedimentation tank there is mounted a member 4, known in the art as a downtake, and surrounding the upper end of the downtake there is an annular filter bed 5. An outlet 6 35 for filtered softened water is tapped into the wall of the sedimentation tank above the level of the filter bed. A mixing plate 7, the function of which will later appear, is mounted adjacent the upper end of the 40 downtake 4. Suitably supported above the sedimentation tank there is a fractionating box 8 having a main outlet 9 which discharges directly upon the mixing plate 7. The fractionating box has a separate normally open outlet 10, having a predetermined 45 cross-sectional area properly proportioned to the area of the main outlet 9 as will later appear. For supplying raw water to the fractionating box there is a raw water pipe 11 which may be equipped with a float 50 valve 12. From the small or regulating outlet 10 of the fractionating box 8 the discharge pipe 13 leads downwardly and discharges into a bucket 14 which is guided for 55 vertical movement in a bucket tank 15, being

designed to float upon the surface of the liquid in the tank. To maintain a constant level of liquid within the bucket tank for any displacement of the bucket, I may provide an outlet 16 tapped into the wall at the 60 desired level. A cable 17 is connected with the bail of the bucket 14 and leads upwardly over a pair of pulleys 18, and is then turned downwardly and attached to the stem of a suitably formed regulating valve 65 19 which is adapted to engage a seat member 20 let into the bottom of the fractionating box 8. The construction and arrangement of the regulating valve 19 is better shown in Fig. 2. For receiving the water entering 70 through the valve 19 there is provided a pipe 21 which I term a displacing fluid pipe which leads downwardly and discharges into a chemical tank 22, which is designed to contain an aqueous solution or mixture 75 of the chemicals used for softening hard water. Near the upper portion of the tank 22 there is provided an overflow opening 23 which discharges into conduit 24 which is adapted to conduct the overflowing chemical 80 to a sump 25 from which it is taken by a centrifugal pump 26 and discharged through a pipe 27, directly upon the surface of the mixing plate 7, there to mingle with the main stream of raw water discharging 85 from the main outlet 9 in the fractionating box. The pump 26 is of such capacity as to empty the sump 25 with a maximum rate of feed of chemicals to the latter.

The operation of my apparatus as above 90 described is as follows:

The raw water entering the box 8 will 95 there be divided into two streams, a main stream which will discharge from the outlet 9 directly from the mixing plate 7, and a regulating stream which will bear a certain predetermined relation to the main stream at all times, and be discharged through the outlet 10 and pipe 13 into the bucket 14. As the latter becomes filled it 100 will sink within the tank 15, thereby pulling the cable 17 and raising the valve 19 from the seat 20. This will permit a certain predetermined quantity of water, according to the size of the valve opening and 105 the elevation of the valve, to flow through the displacer pipe 21 and empty into chemical tank 22 which will have been filled with chemicals up to the level of the outlet 23 therein. As the additional fluid from the 110

displacer pipe enters the chemical tank 22 the chemical therein contained will be diluted and therefore increased, whereby a certain proportion of the diluted chemical 5 will in volume overflow through the outlet 23 and be thereby discharged into the sump 25, to be taken up by the pump 26 and discharged upon the mixing plate 7 where it mingles with the main stream of raw water 10 from the discharge aperture 9.

It will be noted that as the operation of the water softening apparatus continues, the chemical solution within the tank 22 will become more and more dilute, so that any 15 unit volume of this solution will contain a steadily decreasing proportion of active reagent. It is therefore necessary that as the "run" of the apparatus progresses, a larger and larger percentage of the chemical 20 solution be supplied to the sump 25. This result is accomplished by making the valve 19 of proper form, so that as the bucket 14 progressively sinks the effective opening of the valve will be increased in 25 order that the required larger volume of displacing water may discharge from the pipe 21 into the chemical tank 22. As the bucket 14 approaches the bottom of the bucket tank 15, that is, as the run draws 30 near to its close, the dilution of the chemicals in the tank 22 progressively increases until at the end of the run there is practically nothing but pure water in this tank. It will be understood that by the action of 35 the apparatus before described, the parts being properly proportioned in accordance with the operation required of them, the feed of chemicals will be automatically regulated at all times in proportion to the 40 feed of raw water.

It will be understood that the feed of raw water may be controlled in accordance with the demands for softened water, by any of the well known means, these parts of the 45 construction forming no part of my invention. It will also be understood that while I have shown the displacing water as being withdrawn from the fractionating box 8 directly, this is not by any means essential as 50 being possible to take this displacing water from any desired source, so long as the regulating valve 19, or its equivalent be employed.

It will further be understood that as to 55 all the details of construction shown and

described, they are to be regarded as illustrative only and for the purpose of making the invention more clear. The invention is not to be regarded as limited to such details except in so far as such limitations have been included within the terms of the following claims in which it is my intention to claim all novelty inherent in my invention as broadly as is permissible in view of the prior art.

What I claim as new and desire to secure by Letters Patent is:

1. In a water-softening apparatus, means for supplying raw water, means for dividing the water supplied into a main stream and a regulating stream, a bucket tank, a bucket floating therein, means for discharging the regulating stream into the said bucket, a chemical containing tank, an overflow for the said chemical containing tank, means for supplying displacing fluid to the said chemical containing tank, means for regulating the supply of said displacing fluid in accordance with the position of the said bucket, said means operating to supply a progressively greater amount of displacing fluid as the bucket progressively lowers, and means for receiving the overflow from the said chemical containing tank and for mixing it with the main stream of raw water.

2. In a water-softening apparatus, a sedimentation tank, a fractionating box mounted above the said tank, said box having a main outlet discharging directly into the said tank and a regulating outlet discharging separately, a bucket tank, a bucket guided for vertical movement therein, means for conducting the discharge from said regulating outlet to said bucket, a chemical containing tank having an overflow, means for supplying displacing water to the said chemical containing tank, a valve controlling the supply of such displacing water, connections between said valve and said bucket for operating the former by movement of the latter, and means for delivering the diluted chemicals overflowing from the said chemical containing tank into the said sedimentation tank.

CASS L. KENNICOTT.
